UNITED STATES PATENT OFFICE

LEONARD A. BURNHAM, OF GLOUCESTER, MASSACHUSETTS.

IMPROVEMENT IN FISHING-LINE SINKERS.

Specification forming part of Letters Patent No. 58,211, dated September 25, 1866.

To all whom it may concern:

Be it known that I, LEONARD A. BURNHAM, of Gloucester, in the county of Essex and State of Massachusetts, have invented an Improved Fishing-Line Hawse and Swivel; and I do hereby declare the same to be fully described in the following specification and represented in the accompanying drawings, of which—

Figure 1 is a perspective view of it as applied to a sinker. Fig. 2 is a section of it as taken through the hawse and its hook-line supporting rod. Fig. 3 is a top view of the hawse and its connection-rod, which goes through the sinker in manner as shown in Fig. 4, which is a vertical section of the sinker and hawse.

In the drawings, A represents the hook-line supporter, which is provided with eyes *a a* at its extremities for the attachment of the lines of the hooks to it.

The said supporter extends in opposite directions and at or about right angles to a spindle, B, of the hawse, such spindle being usually made of metal or rawhide and leather.

This spindle is inserted and fixed in a cylindrical tube, C, formed with a cylindrical projection, *c*, extending from a shoulder, *b*, as represented. This tube C may have a tapering bore to receive the spindle of the hawse when such spindle is made of flexible materials, such as rawhide and leather, such bore being larger in diameter at its rear end. The said tube C extends into another tube or socket-piece, D,

which has a male screw, *e*, formed on it at its front end. The socket-tube is closed at its rear end and is hinged or jointed to the connection-rod E, which goes up through the sinker S, and may be provided with a swivel, F, arranged at its upper end. The fishing-line is to be attached to the eye of the swivel.

The sinker is to be cast on both the connection-rod and the socket-tube D.

A cylindrical cap, G, to fit to the projection C and against its shoulder *b* is to be screwed on the screw *e*. It serves to keep the swivel tube in place in its socket-tube, in which it can freely revolve.

The socket-tube applied to the sinker, and the swivel-tube applied to the spindle, is a great improvement over the common modes of making a hawse and connecting it to the hook-supporter and the sinker, as it allows the hook-supporter to revolve only in one plane, and therefore prevents fouling of the hooks or their lines, and other difficulties incident to the ordinary modes of applying the hook-supporter to the hawse.

I claim—

The improved swivel-hawse made of the parts C D G, constructed, arranged, and combined with the spindle B and the sinker S, substantially as above set forth.

LEONARD A. BURNHAM.
